UNITED STATES PATENT OFFICE.

ROLAND H. GUINZBURG, OF NEW YORK, N. Y., ASSIGNOR TO I. B. KLEINERT RUBBER COMPANY, OF NEW YORK, N. Y., A CORPORATION OF NEW YORK.

ABDOMINAL REDUCING GARMENT.

Application filed April 29, 1924. Serial No. 709,738.

To all whom it may concern:

Be it known that I, ROLAND H. GUINZBURG, a citizen of the United States, and a resident of the city of New York, county of Queens, and State of New York, have invented a new and useful Improvement in Abdominal Reducing Garments, of which the following is a specification.

This invention relates to a garment adapted to be worn for the purpose of reducing the size of the abdomen, and particularly the upper portion thereof, which is generally termed the diaphragm, and the object of this invention is to provide a garment of this character which will be of such material and so constructed that it will exert a smooth and yielding pressure on those portions of the body intended to be reduced, acting to gently massage and compress the tissues so that a reduction in size of the parts is gradually accomplished without in any way injuring or causing discomfort to the wearer.

A further object of this invention is to provide a garment of the character mentioned above, in which means will be provided for exerting a greater pressure or tension on those portions of the abdomen where the greatest reduction is required, or in other words which will localize the maximum pressure at those points in the front portion of the garment behind which the greatest abdominal protuberance is located.

A still further object of this invention is to provide a belt-like garment which is adapted to extend around the body of the wearer, applying a slight or minimum amount of pressure at the back of the wearer, where no great amount of reduction is required, and applying the greater or maximum amount of pressure or tension on certain parts of the front portion of the body above the waist line.

With these objects, and such other objects as may hereinafter appear, in view, I have devised the particular arrangement of parts hereinafter set forth and more particularly pointed out in the claims appended hereto.

Reference is to be had to the accompanying drawing, forming a part hereof, in which—

Figure 1 is a front elevation of my improved abdominal reducing garment;

Figure 2 is a rear elevation of the same;

Figure 3 is a longitudinal sectional view of the same;

Figure 4 is a view showing the manner in which the garment appears when worn; and

Figure 5 is a perspective view of the separate strip which is secured on the front of the garment.

Throughout the various views of the drawings, similar reference characters designate similar parts.

In the embodiment of my invention disclosed in the accompanying drawing, 1 indicates the front section of the garment, the same being preferably made of a highly elastic material impervious to moisture such as sheet rubber or the like. The upper edge of the front section converges upwardly to a central point 3, and the lower edge 4 is gradually curved downwardly, as clearly indicated in Figure 1, so that the widest portion of the front section is located at its central point and the diaphragm is properly covered by said front section.

The edges 2 and 4 of the front section are suitably reinforced by strips 5 and 6, which are of expandible material so that they may expand with and as part of the front section. The ends of the front section terminate in reinforces 7 and 8 which are preferably made up of a number of layers or thicknesses of a tough, inexpandible fabric, and these reinforces tend to hold the garment out flat and evenly on the body, preventing wrinkling or bunching of the garment when it is worn.

Extending between and connecting the two reinforces 7 and 8 is a separate strip 9 which is of expandible material and which is not secured for its length to the face of the front section 1 and is expandible independently of said front section. As will be seen, this strip extends longitudinally of the front section, but is of much less width than the same. The strip 9 is preferably located on the inner face of the front section but it may be located on the outer face of the same if desired. The strip 9 throughout its entire length is separated from the face of the front section 1, but it has its ends 10 and 11 secured to, or secured between the reinforces 7 and 9 and the face of the front section. The strip 9 is provided with lateral extensions 12 and 13 which project transversely of the

front section of the garment and which have their ends secured at the opposite or upper and lower edges of the garment at the points where reinforces 14 and 15 are located.

The strip 9 and its lateral extensions 12 and 13 is so formed as to properly embrace the front or diaphragm portion of the body of the wearer and holds the same with a firm yet yielding pressure, imparting a gentle massaging action to the same, gradually causing the reduction in size of the upper portion of the abdomen.

The formation of a strip, such as at 9, on the front of the garment provides two separate thicknesses of material which co-operate to impart greater tension and a greater pressure on those parts of the body which lie behind it, which are those parts where the greatest reduction is required.

The back section of the garment is shown at 16 and the same may be of any expansible material impervious to moisture, such as rubber similar to the front section. The longitudinal edges of the rear section are suitably reinforced by strips 17 and 18, and one end of the rear section terminates in a reinforce 19 similar to the reinforces 7 and 8, previously described.

The garment is supported on the wearer by shoulder straps 20 and 21 which connect the front and rear sections as shown.

In Figures 2 and 3, the garment is shown as it appears in use, where it will be seen that the same forms a continuous belt-like garment surrounding the body and extending upwardly from the waist line with the separate strip 9 innermost and against the body of the wearer. The ends of the garment are united together by any suitable fasteners such as the eyes 22 secured on the reinforce 19 which engage with hooks located on the reinforce 11. When so united the joint or connection of the two ends of the garment is located at a point below one of the wearer's arms, while the reinforce 7 is located at a point below the other arm, the front section 1 being thus drawn taut between the reinforces 7 and 8 across the front of the wearer's body over the diaphragm where the reduction is desired.

A depending strip 23 has its upper end

secured to the front section 1, the reinforce 15 being provided to prevent strain on the front section. The lower end of the strip 23 is provided with a loop 24 which is adapted to engage with a fastening member or a button on a corset or other article of apparel to hold down the garment, preventing the same from moving up on the body of the wearer, and also holding the lateral portions 12 and 13 of the separate strip under tension against the body.

The back section of the garment is of substantially thin rubber and the front section is of similar rubber, except where the strip 9 is located and thickness, tension and pressure is provided. The thin rubber sections have considerable elasticity and consequently do not impart a pressure as great as that imparted by the front portion of the garment co-operating with the strip 9 which is the location where the greater pressure is required.

What I claim is:

1. An article of the class described comprising a body-embracing elastic band made of material impervious to moisture, said band having an elastic front section, the ends of which terminate in inexpansible reinforces, and a continuous elastic strip free and independent of the front section for its length and extending across the same and connecting one of the reinforces with the other.

2. An article of the class described comprising a garment having a front section and a rear section joined to form a continuous strip adapted to extend about the body, said front and rear sections being composed of an elastic material impervious to moisture, an elongated strip of elastic material free and independent of the front section extending longitudinally across the same and having its ends connected to the face of the front section at spaced points, said strip having lateral extensions, at the ends of which are secured at the upper and lower edges of the front section.

Signed at the city of New York, county of Queens and State of New York, this 25 day of April, 1924.

ROLAND H. GUINZBURG.
